US0D1100864S

(12) **United States Design Patent** (10) **Patent No.:** **US D1,100,864 S**
(45) **Date of Patent:** **** Nov. 4, 2025**

(54) **REMOTE CONTROL**

(71) Applicant: **Lutron Technology Company LLC**,
Coopersburg, PA (US)

(72) Inventors: **Gregory Altonen**, Easton, PA (US);
Chris Dimberg, Easton, PA (US);
Jason C. Killo, Emmaus, PA (US);
Matthew Philip McDonald,
Phoenixville, PA (US); **Daniel L.**
Twaddell, Allentown, PA (US)

(73) Assignee: **Lutron Technology Company LLC**,
Coopersburg, PA (US)

(**) Term: **15 Years**

(21) Appl. No.: **29/914,048**

(22) Filed: **Oct. 12, 2023**

Related U.S. Application Data

(63) Continuation of application No. 29/848,518, filed on Aug. 3, 2022, now Pat. No. Des. 1,005,244, which is a continuation of application No. 29/812,465, filed on Oct. 21, 2021, now Pat. No. Des. 962,876, which is a continuation of application No. 29/771,303, filed on Feb. 22, 2021, now Pat. No. Des. 936,617, which is

CLAIM

The ornamental design for a remote control as shown and described.

DESCRIPTION

FIG. 1 is a front perspective view of a remote control showing our new design;

FIG. 2 is a front view thereof;

FIG. 3 is a left side view thereof;

FIG. 4 is a right side view thereof;

FIG. 5 is a top view thereof; and,

FIG. 6 is a bottom view thereof.

The broken lines illustrate structure or features which form no part of the claimed design.

1 Claim, 4 Drawing Sheets

Related U.S. Application Data

a continuation of application No. 29/640,715, filed on Mar. 16, 2018, now Pat. No. Des. 913,254.
